UNITED STATES PATENT OFFICE.

JOHN P. DORAU, OF NORTH FOND DU LAC, WISCONSIN.

IRONING BOARD.

Application filed May 31, 1921. Serial No. 473,606.

To all whom it may concern:

Be it known that I, JOHN P. DORAU, a citizen of the United States, residing at North Fond du Lac, in the county of Fond du Lac and State of Wisconsin, have invented certain new and useful Improvements in Ironing Boards; and I do declare the following to be a full, clear, and exact description of the invention, such as will enable others skilled in the art to which it appertains to make and use the same.

This invention relates to an improved ironing table and one object of the invention is to provide a table having a top in the form of an ironing board and having improved supporting means for the ironing board, the supporting means being foldable so that it may be moved from a set up or operative position to a folded position against the under face of the board.

Another object of the invention is to provide a support so constructed and assembled that it may fold flat against the underface of the board and further so constructed that the supporting structure may be held in the folded or inoperative position by a single fastener, this fastener engaging a support for one end of the board when in the folded position and the support when in a folded position engaging a second support, to hold the second support in a folded position.

Yet another object is to provide an ironing board having a supporting frame with a springy framing member (preferably an inclined brace) active by virtue of its resiliency to retain the frame in operative position.

A still further object is to make provision for shifting the upper end of the leg structure which supports one end of the board, to different positions along said board so as to either expose the narrow end thereof for reception in different articles of apparel or to give ample room between the leg structure and the opposite end of the board to accommodate a long skirt or the like.

Another object of the invention is to provide improved means for connecting the support for one end of the board with side strips which are pivotally connected with the board and have the second support pivotally connected with their free ends, so that the side strips and two supports may be swung to the folded position against the underface of the board.

Another object of the invention is to pro-

vide a board having a construction which will permit of a covering sheet being easily and quickly fastened upon the board and securely held in place, but at the same time 60 permitted to be easily removed when desired.

This invention is illustrated in the accompanying drawings, wherein:

Figure 1 is a side elevation of the ironing board.

Figure 2 is a plan view showing the table folded.

Figure 3 is a side elevation showing a modified construction. 70

Figure 4 is a fragmentary view showing a latch used in connection with the structure of Fig. 3.

Figure 5 is a fragmentary view in elevation showing a modified construction. 75

Figure 6 is a bottom plan view of the structure shown in Fig. 5.

Figure 7 is a side elevation showing a modified construction.

Figure 8 is a fragmentary sectional view 80 through the board.

Figure 9 is a fragmentary bottom plan view of the board.

This improved ironing table is provided with a top or ironing board 1 which will 85 have a groove 2 cut from its underface and adjacent its edge faces, so that a cover 3 in the form of a sheet or blanket may be drawn tightly upon the board and have its marginal portions folded into this groove 2 as shown 90 in Fig. 8 and secured by removable pins 4 which will pass through openings 5 formed in the board as shown. It is of course understood that as many pins will be provided as necessary to hold the cover tightly in place. Supporting means is provided for the board 95 and will include supports 6 and 7 and side strips or braces 8 which will be connected with the board and also have engagement with the supports 6 and 7. In the form shown in Figs. 1 and 2, the side strips 8 are pivotally connected with the depending ears of a cross strip or bracket 9 and the side bars 10 of the support 6 are pivotally connected with a second cross strip or bracket 100 11 secured to the underface of the board in spaced relation to the bracket 9. These side bars 10 are connected by a bracing strip or board 12 and adjacent their pivoted ends carry a rod 13 which extends beyond the side bars 10 for fitting into openings formed 110 in the side strips 8. This rod 13 therefore

provides means for releasably connecting the support 6 with the side strips 8, releasing being accomplished by spreading the side strips a sufficient distance to move the 5 ends of the rod 13 out of the opening in the side strips. It will thus be seen that when it is desired to fold the supporting structure, the support 6 can be released from the side strips 8 and this support 6 swung 10 against the under-face of the board 1. The side bars 14 of the support 7 are pivotally connected with the strips 8 and at their pivoted ends are braced by a cross strip or board 15 which carries a latch 16 pivotally 15 mounted and adapted to be swung into engagement with a keeper 17 carried by the board when the support 7 is in the folded position of Fig. 2. The free end portions of these side bars 14 are braced by a cross rod 20 18 and the end portions of these side bars are adapted to fit into sockets 19 of the board when the table is in a set up or operative position. From an inspection of Fig. 2, it will be seen that when the table is folded, 25 the end portion of the support 7 will extend partially across the cross strip 12 on the support 6 and therefore the support 7 will serve to retain the support 6 in the folded position. The latch 16 will retain the support 7 in the folded position and thus the supporting structure for the board will be 30 securely held in the folded position close against the under face of the board.

In Fig. 3, there has been shown a slightly modified construction in which the bracket 11 will be done away with and the upper end 35 portions of the side bars 10 of the support 6 will fit into sockets of the board similar to the sockets 19. The rod 13 has its end portions fitting into the openings of the side strips 8 to pivotally mount the support 6 and will be of sufficient length to prevent this support 6 from becoming detached 40 from the strips 8 accidentally. There has also been provided latching means in the 45 form of a hook 20 of resilient metal loosely connected with a lever handle 21 which is pivotally connected with a cross strip 22 taking the place of the rod 18. Screw-eyes 50 23 will be mounted in the center of the board between the rows of sockets 19 and when the table is set up, the hook 20 will be brought into engagement with one of the 55 screw-eyes and the support 7 will be secured in the operative position.

In the form shown in Figs. 5 and 6, the side bars of the support 6 are pivotally connected with the bracket 11 and the side strips 60 8 are pivotally connected with the side bars of the support 6 after the manner in which they are connected in the form shown in Fig. 1. Instead of having the side strips 8 pivotally connected with a bracket 9, there 65 has been provided a cross rod 24 between the

side strips 8 which cross rod is to fit into the groove or seat 25 formed in the socket block 26. This socket block 26 is secured upon the underface of the board 1 and carries a latch 27 which may be swung to engage the rod 24 and retain it in the seat 25. It will thus be seen that in this form, the support 6 is pivotally connected with the board instead of releasably engaging the same as in Fig. 2 and the side strips 8 are releasably connected with the board instead of being pivotally connected with a bracket 9.

In the form shown in Fig. 7, the side bars of the support 6 are pivotally connected with the bracket 11 and the ends of the side strips 8 are pivotally connected with a bracket 9. The cross rod 13 of the support 6 engages the under edge faces of the side strips 8 and the portions of the strips 8 which are engaged by the cross rod 13 are 85 slightly cut away, the cut portion of each strip terminating in a recess or pocket 28. Resilient retainer strips 29 are secured to the under edges of these side strips 8 and engage the cross rod 13 to hold the rod in 90 engagement with the side strips 8.

When this table is in use, it is set up as shown in Figs. 1 and 3 and a firm table will be provided. When it is desired to fold the table and put it away, the support 7 95 will be swung out of engagement with the board and the support 6 and side strips 8 swung against the underface of the board. The support 7 will then be swung to the position of Fig. 2 with its free end portion 100 engaging the free end portion of the support 6. The latch 16 will then be swing to an operative position and the supporting structure will be held folded.

Attention is directed to the fact that in 105 all forms of the invention except that disclosed in Fig. 3, it is necessary to spring the brace 8 downwardly in order that the leg structure 7 may be swung, for instance, from the position shown in Fig. 1, to the 110 outermost of the sockets 19. By thus placing the brace under tension while adjusting the leg structure 7, such tension is utilized to retain the leg structure in engagement with the sockets. Attention is further directed to the fact that when the leg structure 7 is swung inwardly to the position shown in Fig. 1, the narrow end of the board 1 projects to quite an extent beyond said leg structure so that it may be inserted in different articles of apparel when pressing the latter. When this leg structure is swung entirely out of engagement with the board 1 as shown in dotted lines in Fig. 1, a skirt 125 or the like may be passed entirely around the board, after which said leg structure may be swung again into operative relation with the sockets 19. If the skirt or the like be rather long, the structure 7 may be engaged with the outermost of said sockets so as to 130

readily accommodate the article between the two leg structures 6 and 7.

I claim:

1. An ironing board, side strips pivotally connected with said board beneath one end thereof, a support pivotally connected with the board in spaced relation to the mounting of said side strips and comprising side bars and a cross rod engaging the under faces of the side strips, the side strips being provided with recesses receiving said cross rod, and resilient strips secured to the side strips and engaging the cross rod to hold the same in sliding engagement with the side strips, said side strips and support folding up against the underface of the board with the support positioned between the side strips, a support pivotally connected with the free ends of the side strips for engaging the second end portion of the board when in an operative position and for engaging and securing the first support when in a folded position, and means for locking the second support in a folded position.
2. An ironing board, side strips pivotally mounted beneath one end of said board, a support connected with the board in spaced relation to the pivotally mounted ends of said side strips and extending between said strips, guide means extending from said support and engaging the under edge faces of said side strips, the side strips being provided with recesses for receiving said guide means, resilient strips carried by said side strips for engaging said guide means to

slidably retain the guide means in said recesses, and a support for extending between the free ends of said side strips and said board when the board is in a position for use.

3. A foldable ironing board comprising a pivoted leg structure at one end of the board, a brace formed of springy material declining from said leg structure to a point beneath the other end of the board, said brace having pivotal connection with the upper portion of said leg structure and being associated with said board in a manner to limit downward swinging upon said pivotal connection, and an additional leg structure pivoted to the lower end of said brace, the lower side of said board having a socket in which the upper end of said additional leg structure is receivable when said brace is sprung slightly downward.

4. An ironing board having longitudinally spaced pairs of sockets in the lower side of one of its ends, a pair of connected substantially vertical legs pivoted to the other end of said board, a second pair of connected substantially vertical legs having reduced upper ends engageable with a pair of said sockets, and a pair of inclined one-piece springy braces pivoted at their lower ends to the lower ends of said second pair of legs and having connection with said first named pair of legs and the board.

In testimony whereof I have hereunto set my hand.

JOHN P. DORAU.
